REVERSIBLE SIGN

Theodore Vladeff, 214 Fox Bldg., Detroit, Mich.

Filed May 23, 1963, Ser. No. 75,019

Term of patent 14 years

(Cl. D1—12)

FIGURE 1 is a front elevational view of a sign embodying my invention;

FIGURE 2 is a rear elevational view of the same;

FIGURE 3 is a side elevational view thereof;

FIGURE 4 is a top plan view; and

FIGURE 5 is a sectional view taken substantially on the line V—V of FIGURE 1 and looking in the direction of the arrows.

The lettering and ornamentation are in intaglio upon the internal surface of the smooth exterior faces, as best illustrated in FIG. 5.

I claim:

The ornamental design for a reversible sign, substantially as shown and described.
